CLAIM

The ornamental design for a dinosaur car toy, as shown and described.

DESCRIPTION

FIG. 1 is a perspective view of a dinosaur car toy, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view showing the dinosaur car toy, in another state.

The broken lines in the drawings depict portions of the dinosaur car toy, that form no part of the claimed design.
